ABSTRACT

A mold apparatus for casting a cylinder block having a cast-in cylinder liner by installing the cylinder liner inside a cavity and pouring a melt into the cavity, the mold apparatus includes a first mold and a bore pin. The first mold defines a deck surface of the cylinder block. The bore pin is in the first mold so as to hold the cylinder liner inside the cavity when the mold is closed. The bore pin is configured to hold the cylinder liner interposed by a gap, and the gap is arranged so as to enable gas produced during the cast-molding to be discharged therethrough.

MOLD APPARATUS FOR CASTING CYLINDER BLOCK**CROSS-REFERENCE TO RELATED APPLICATIONS**

This application claims priority to Japanese Patent Application No. 2013-156144 filed in Japan on Jul. 26, 2011, the contents of which are hereby incorporated herein by reference.

BACKGROUND**Field of the Invention**

The present invention relates to a mold apparatus for casting a cylinder block, for cast-molding a cylinder block having a cast-in cylinder liner by installing the cylinder liner inside a cavity and pouring a melt into the cavity.

Background Information

A configuration of this kind of mold apparatus for casting a cylinder block hitherto has been proposed (see, for example, Japanese Patent No. 4326395), in which a movable mold is formed by insertion-coupling a bore pin for holding a cast-in sleeve, on an inner perimeter of a water jacket-forming insert, the mold is closed in a state in which the cast-in sleeve is fitted on the bore pin, so that one end face in a longitudinal direction of the cast-in sleeve contacts with a step part on the stepped bore pin, and the mold is then filled with an aluminum melt, whereby an overcasting-type cylinder block, in which an end face on a deck-surface side on the cast-in sleeve is enclosed by the aluminum melt, is cast-molded.

In this apparatus, a surface-roughened part is formed on the insertion-coupling surface between the bore pin and the water jacket, and gas accumulating inside an elongated blocked-off cavity formed by the end face on the deck-surface side of the cast-in sleeve, a movable core, and the step part of the bore pin is discharged from the surface-roughened part. That is, the surface-roughened part is used as a gas discharge passage.

SUMMARY

Incidentally, the gas produced during casting contains carbide (release agent residue) produced by burning of an oil component in a release agent, or aluminum slag, or the like, and the carbide (release agent residue), aluminum slag, or the like, therefore adheres to the gas discharge passage when the produced gas passes through the gas discharge passage. The gas discharge passage also becomes clogged by accumulation of the carbide (release agent residue) or aluminum slag, and a periodic operation of cleaning of the gas discharge passage therefore becomes necessary. In the above-described cylinder block casting mold, in order to remove the carbide (release agent residue), aluminum slag, or the like, accumulating in the gas discharge passage, the movable mold must be disassembled, that is, the insertion-coupling between the water jacket-forming insert and the bore pin must be decoupled, and the cleaning operation for removing the carbide (release agent residue), aluminum slag, or the like, becomes extensive. The casting operation must be interrupted for such cleaning operation, and therefore the operation efficiency of the casting operation also is lowered.

The present invention was created in consideration of the above, and an object thereof is to provide a technique that contributes to improvement of operation efficiency of the casting operation.

2

The mold apparatus for casting a cylinder block of the present invention adopts the following means in order to achieve the above-described object.

According to a preferred aspect of the mold apparatus for casting a cylinder block according to the present invention, there is configured a mold apparatus for casting a cylinder block adapted for cast-molding a cylinder block having a cast-in cylinder liner by installing the cylinder liner inside a cavity and pouring a melt into the cavity. The mold apparatus for casting a cylinder block comprises a first mold for defining a deck surface of the cylinder block; and a bore pin provided in the first mold so as to hold the cylinder liner inside the cavity when the mold is closed. The mold apparatus is configured so that the bore pin holds the cylinder liner interposed by a gap. The mold apparatus also is configured so that gas produced during the cast-molding is discharged via the gap. "Deck surface" in the present invention typically corresponds to a surface that fits with a cylinder head. "Gap" in the present invention typically corresponds to a gap produced by dimensional deviation between the bore pin and the cylinder liner, but ideally includes a gap produced between an uneven surface from surface roughness of the bore pin and an uneven surface from surface roughness of the cylinder liner, or a gap actively provided between the bore pin and the cylinder liner.

According to the present invention, the configuration utilizes a cylinder liner that is exchanged each time a cylinder block is cast-molded, as a constituent element of the gas discharge path for discharging gas produced during cast-molding. The accumulation of carbide (release agent residue), or the like, in the gas discharge path therefore can be effectively prevented. The frequency of the operation of cleaning of the gas discharge path thereby can be reduced, and the time required for planning or the casting preparation operation can be shortened. That is, the casting cycle can be shortened. The operation efficiency of the casting operation can be improved as a result. Even if carbide (release agent residue), or the like, adheres to the side of the bore pin, being one constituent element of the gas discharge path, the carbide (release agent residue), or the like, can be easily removed using a brush, or the like, in a state in which the bore pin is placed in the first mold, and therefore the burden on the operator associated with the cleaning operation also can be alleviated.

According to another aspect of the mold apparatus for casting a cylinder block according to the present invention, the mold apparatus further comprises a water jacket-forming insert surrounding the cylinder liner held by the bore pin when the mold is closed. The mold apparatus also is configured so that the gas that has entered into a space inside the cavity is discharged via the gap, the space being formed by the cylinder liner held by the bore pin and by the water jacket-forming insert.

According to the present aspect, gas accumulating in an elongated blocked-off space formed by the cylinder liner and the water jacket-forming insert can be discharged. Formation of a blowhole or the like, in the part corresponding to the elongated blocked-off space in the cylinder block can thereby be effectively prevented. The close adhesiveness of the cylinder liner to the part corresponding to the elongated blocked-off space in the cylinder block also can be improved. The quality of the cylinder block as a manufactured product can be improved as a result.

According to another aspect of the mold apparatus for casting a cylinder block according to the present invention, the bore pin has a shaft part with which the cylinder liner is

fitted, and an enlarged-diameter part formed to a larger diameter than the shaft part. The enlarged-diameter part is provided closer to the side of the first mold than to the shaft part. The mold apparatus also is configured so that the cylinder liner is held by the bore pin in a state in which longitudinal-direction movement of the cylinder liner is restricted by the enlarged-diameter part when the mold is closed, and is configured so that the gas that has entered into a space inside the cavity is discharged via the gap provided between the bore pin and the cylinder liner, the space being formed by a longitudinal-direction end face of the cylinder liner, the enlarged-diameter part, and the water jacket-forming insert.

According to the present aspect, when cast-molding an overcasting-type cylinder block in which the face in the longitudinal direction of the cylinder liner, that is, the end face on the deck surface side is enclosed by melting, gas accumulating in the elongated blocked-off space formed by the longitudinal-direction end face of the cylinder liner, the enlarged-diameter part, and the first mold can be discharged. Formation of a blowhole or the like, in the part corresponding to the elongated blocked-off space in the cylinder block can thereby be effectively prevented. The close adhesiveness of the cylinder liner to the part corresponding to the elongated blocked-off space in the cylinder block also can be improved. The quality of the overcasting-type cylinder block as a manufactured product can be improved as a result.

According to another aspect of the mold apparatus for casting a cylinder block according to the present invention, the gap is configured to enable inflow of the gas but prohibit inflow of the melt.

According to the present aspect, gas produced during cast-molding can be discharged effectively. The operation efficiency of the casting operation can be improved as a result.

According to another aspect of the mold apparatus for casting a cylinder block according to the present invention, the bore pin has a recessed part formed on an outer perimeter surface, and a communicating path communicating between the recessed part and the outside of the mold apparatus for casting a cylinder block. "Connecting between the recessed part and the outside of the mold apparatus for casting a cylinder block" in the present invention ideally includes a mode in which the communicating path directly communicates between the recessed part and the outside, as well as a mode in which the communicating path communicates between the recessed part and the outside via another communicating path.

According to the present aspect, gas passing through the gap between the bore pin and the cylinder liner can be discharged to the outside using a communicating path communicating between the recessed part formed on the outer perimeter surface of the bore pin and the outside of the mold apparatus for casting a cylinder block.

According to another aspect of the mold apparatus for casting a cylinder block according to the present invention, the recessed part is configured as an annular groove continuing in a circumferential direction.

According to the present aspect, because the recessed part is configured as an annular groove, a recessed part having a large capacity can be assured with a simple configuration. The flow speed of the gas passing through the gap between the bore pin and the cylinder liner thereby can be reduced in the annular groove, and the gas can be effectively discharged from the communicating path to the outside via the annular groove. The operation efficiency in the casting operation can be improved as a result.

According to another aspect of the mold apparatus for casting a cylinder block according to the present invention, the communicating path has a first hole opened in a direction from the recessed part toward the inside of the shaft part, and a second hole opened in a direction from the first hole toward the first mold. "Direction toward the inside of the shaft part" in the present invention typically corresponds to a direction perpendicular to the longitudinal direction of the shaft part, but ideally includes a direction inclined toward the longitudinal direction of the shaft part. "Direction from the first hole toward the first mold" also typically corresponds to a direction following the longitudinal direction of the shaft part, but ideally includes a direction inclined toward the longitudinal direction of the shaft part.

According to the present invention, because the configuration is such that the route for discharging gas passing through the gap between the bore pin and the cylinder liner to the outside is formed inside the bore pin, complication of the route for discharging the gas to the outside can be prevented. Because only opening a hole is sufficient, the route for discharging the gas to the outside can be configured simply.

According to another aspect of the mold apparatus for casting a cylinder block according to the present invention, the recessed part has an axial groove connected to the annular groove and provided extending in a longitudinal-axis direction of the bore pin from the annular groove toward a leading end side of the bore pin. The first hole is formed on the leading end side of the axial groove.

According to the present aspect, the position of the formation of the annular groove on the bore pin and the position of formation of the first hole in the bore pin can be provided in a state being separated in the axial direction. That is, the annular groove can be provided near the end part of the bore pin which is connected to the first mold. In other words, the annular groove can be provided on the part of the bore pin near the deck surface side of the cylinder liner where gas easily accumulates. On the other hand, the first hole can be provided near the leading end side of the bore pin on the opposite side of the first mold so that clogging of the hole is easily confirmed by eye. The gas discharge performance and visibility of the gas discharge path can be achieved simultaneously.

According to another aspect of the mold apparatus for casting a cylinder block according to the present invention, the mold apparatus further comprises a vacuum suction device for rendering the inside of the cavity into a vacuum state. The mold apparatus also is configured so that the communicating path communicates between the recessed part and the vacuum suction device.

According to the present aspect, because the configuration is such that the communicating path communicates between the recessed part and the vacuum suction device, the gas can be discharged effectively. The operation efficiency in the casting operation can be improved as a result.

According to the present invention, the operation efficiency of the casting operation can be improved.

BRIEF DESCRIPTION OF THE DRAWINGS

Referring now to the attached drawings which form a part of this original disclosure.

FIG. 1 is a configuration diagram schematically illustrating the configuration of the mold apparatus according to an embodiment of the present invention.

FIG. 2 is an external view illustrating the general appearance of the bore pin.

FIG. 3 is an external view illustrating the general appearance of the bore pin.

FIG. 4 is an enlarged sectional view illustrating in enlargement the state of the bore pin and the cylinder liner when the mold is closed.

FIG. 5 is an explanatory diagram illustrating the manner of cast-molding using the mold apparatus according to an embodiment of the present invention.

DETAILED DESCRIPTION OF EMBODIMENTS

Preferred embodiments of the present invention are next described using examples.

Examples

FIG. 1 is a configuration diagram schematically illustrating the configuration of the mold apparatus 1, FIGS. 2 and 3 are external views illustrating the general appearance of the bore pin, and FIG. 4 is an enlarged sectional view illustrating in enlargement the state of the bore pin 10 and the cylinder liner 60 when the mold is closed. The mold apparatus 1 according to the present embodiment is provided with a movable mold 2, a fixed mold 4, a movable core 6, a water jacket-forming insert 8 fixed to the movable mold 2, and a bore pin 10 fixed to the water jacket-forming insert 8, as illustrated in FIG. 1. A vacuum suction device 50 is connected to the mold apparatus 1. The mold apparatus 1 and the vacuum suction device 50 correspond to the "mold apparatus for casting a cylinder block" in the present invention, and the movable mold 2 corresponds to the "first mold" in the present invention, as one example of a working configuration. The water jacket-forming insert 8 corresponds to the "water jacket-forming insert" in the present invention, and the bore pin 10 corresponds to the "bore pin" in the present invention, as one example of a working configuration. The vacuum suction device 50 corresponds to the "vacuum suction device" in the present invention as on example of a working configuration.

The movable mold 2 is a main part configuring the main unit of the mold apparatus 1 as illustrated in FIG. 1. The movable mold 2 is configured to define in particular an upper deck surface inside a cavity 30 configuring the shape of the cylinder block as a manufactured product. An installation hole 2a for insertion-coupling the water jacket-molding insert 8, to be described later, is formed in the movable mold 2. An extrusion mechanism not illustrated is provided on the movable mold 2 in order to remove the cylinder block as a cast-molded manufactured product.

The fixed mold 4 is a main part configuring the main unit of the mold apparatus 1 and configures the cavity 30 just as the movable mold 2, as illustrated in FIG. 1. The fixed mold 4 is provided with a bulging part 4a for forming a crankcase. A flat surface 4b being flat is formed on a top part of the bulging part 4a, and a recessed part 4c being trapezoidal in section is formed in a center part of the flat surface 4b. Here, although not illustrated, the recessed part 4c is configured as a groove following the direction of a cylinder array (the direction of planes of paper in FIG. 1) on a cylinder block as a manufactured product. An inlet bush not illustrated is provided on the fixed mold 4 in order to inject a melt.

The movable core 6 is a main part configuring the main unit of the mold apparatus 1 and configures the cavity 30 just as the movable mold 2 and the fixed mold 4, as illustrated in FIG. 1. The movable core 6 forms an undercut part on the cylinder block as a manufactured product.

The water jacket-forming insert 8 is configured from the installation part 8a and the water jacket-forming part 8b as illustrated in FIG. 1. The installation part 8a is configured in a cylindrical shape having a hole 8c formed in the center, and has an outer diameter roughly the same diameter as an inner diameter of the movable mold 2. The water jacket-forming insert 8 is integrally connected to the movable mold 2 by insertion-coupling of the installation part 8a in the installation hole 2a of the movable mold 2. In the example, 5 the water jacket-forming insert 8 is configured as being integrally connected to the movable mold 2 after being formed separately from the movable mold 2, but the water jacket-forming insert 8 may be configured being integrally molded on the movable mold 2. In this case, the water jacket-forming insert 8 corresponds to the "first mold" in the present invention as one example of a working configuration.

The water jacket-forming part 8b is a part forming a water jacket on the cylinder block as a manufactured product, and 10 is configured in a roughly cylindrical shape, as illustrated in FIG. 1. An outer diameter of the water jacket-forming part 8b is formed to roughly the same diameter as the outer diameter of the installation part 8a, and an inner diameter of the water jacket-forming part 8b is configured to be larger 15 than an outer diameter of the cylinder liner 60 cast in the cylinder block as a manufactured product. That is, the water jacket-forming part 8b is configured to surround the cylinder liner 60 held by the bore pin 10, to be described later, whereby a space (one part of the cavity 30) is configured 20 between an inner perimeter surface of the water jacket-forming part 8b and an outer perimeter surface of the cylinder liner 60, and the cylinder liner 60 is cast in by the melt by flowing of the melt into the space (one part of the cavity 30). The water jacket-forming insert 8 projects into 25 the cavity 30 and configures a core when the mold is closed. The water jacket-forming part 8b surrounding the cylinder liner held by the bore pin 10 corresponds to the "water jacket-forming insert surrounding the cylinder liner held by the bore pin" in the present invention as one example of a 30 working configuration.

The bore pin 10 is configured with an installation part 10a fitted into the hole 8c of the water jacket-forming insert 8, a flange-form enlarged-diameter part 10b formed continuing on the installation part 10a, and a holding part 10c for 35 holding the cylinder liner 60, as illustrated in FIGS. 2 and 3.

The installation part 10a is configured in a cylindrical shape, and has an outer diameter roughly the same diameter as an inner diameter of the hole 8c of the water jacket-forming insert 8, as illustrated in FIGS. 2 and 3. The bore pin 50 10 is integrally connected to the water jacket-forming insert 8 by insertion-coupling of the installation part 10a in the hole 8c. In the example, the bore pin 10 is configured as being integrally connected to the water jacket-forming insert 8 after being formed separately from the water jacket-forming insert 8, but the bore pin 10 may be configured being integrally molded on the water jacket-forming insert 8.

The enlarged-diameter part 10b is formed to a larger diameter than the installation part 10a and the holding part 60 10c, as illustrated in FIGS. 2 and 3. An end face 11a on the side of the installation part 10a, among end faces of a radially-extended extended part of the enlarged-diameter part 10b, contacts with the installation part 8a of the water jacket-forming insert 8. The bore pin 10 is thereby positioned 65 in an axial direction against the water jacket-forming insert 8. An end face 11b on the side opposite the end face 11a, that is, on the side of the holding part 10c, among the

end faces of the radially-extended extended part of the enlarged diameter part **10b**, restricts movement in a longitudinal-axis direction of the cylinder liner **60** when the mold is closed. The enlarged-diameter part **10b** corresponds to the “enlarged-diameter part” in the present invention as one example of a working configuration.

The holding part **10c** is configured to a long cylindrical shape extending in a longitudinal direction, as illustrated in FIGS. 2 and 3. The holding part **10c** has an outer diameter such that a prescribed gap **CL1** is formed between the inner perimeter surface **10c** of the holding part **10c** and the inner perimeter surface of the cylinder liner **60** when the mold is closed **60**, and has a long axis such that a prescribed gap **CL2** is formed between the end face **11b** of the enlarged-diameter part **10b** and the end face **60a** in the longitudinal-axis direction of the cylinder liner **60** when the mold is closed, as illustrated in FIG. 4. The holding part **10c** corresponds to the “shaft part” in the present invention, and the end face **60a** in the longitudinal-axis direction of the cylinder liner **60** corresponds to the “longitudinal-direction end face of the cylinder liner” in the present invention, as one example of a working configuration.

That is, the holding part **10c** is set to a fitting tolerance such that the prescribed gap **CL1** is provided between the outer perimeter surface of the holding part **10c** and the inner perimeter surface of the cylinder liner **60**, even with consideration of the outer diameter tolerance of the holding part **10c** and the inner diameter tolerance of the cylinder liner **60**, and is set to a tolerance relationship such that the prescribed gap **CL2** is provided between the end face **11b** of the enlarged-diameter part **10b** and the end face **60a** in the longitudinal-axis direction of the cylinder liner **60** when the mold is closed, even with consideration of the axial length tolerance of the holding part **10c** and the axial length tolerance of the cylinder liner **60**. The tolerance is set to a value such that the aluminum melt does not intrude into the prescribed gaps **CL1** and **CL2** even when the prescribed gaps **CL1** and **CL2** fluctuate in a direction to become maximal. Therefore, the gap **CL1** and the gap **CL2** are configured to enable inflow of the gas produced during cast-molding but prohibit inflow of the aluminum melt. A median value of the tolerance for the prescribed gaps **CL1** and **CL2** is preferably set such that the prescribed gaps **CL1** and **CL2** become maximal within a limit that the aluminum melt does not intrude. The prescribed gaps **CL1** and **CL2** correspond to the “gap” in the present invention as one example of a working configuration. The mode setting to fitting tolerance such that the prescribed gaps **CL1** and **CL2** become maximal within a range of the gap through which the aluminum melt does not intrude corresponds to being “set to a maximum gap allowing inflow of the gas but disallowing inflow of the melt” in the present invention as one example of a working configuration.

An annular groove **10d** is formed on the holding part **10c** in a position further toward the installation part **10a** (upward in FIGS. 2 and 3) from the center in the longitudinal direction, as illustrated in FIGS. 2 and 3. By thus forming the annular groove **10d** further toward the installation part **10a**, gas accumulating in an elongated blocked-off space **S** to be described later (one part of the cavity **30**, being a space formed by the end face **60a** in the longitudinal-axis direction of the cylinder liner **60**, the enlarged-diameter part **10b** of the bore pin **10**, and the end face of the installation part **8a** of the water jacket-forming insert **8** when the mold is closed) can be effectively discharged. The annular groove **10d** corre-

sponds to the “recessed part” and the “annular groove” in the present invention as one example of a working configuration.

A long groove **10e** having one end connected to the annular groove **10d** and having the other end placed extending with a prescribed length in the longitudinal direction toward the leading end side of the bore pin **10** also is formed on the holding part **10c**. A hole **12a** in a direction going toward the inside of the holding part **10c** is formed on the leading end part (the part on the side opposite the annular groove **10d**) of the long groove **10e**. That is, the hole **12a** is opened in a direction perpendicular to the longitudinal direction of the holding part **10c**. The long groove **10e** is formed to a length to an extent that the hole **12a** is visible from the outside even in a state in which the bore pin **10** is installed in the water jacket-forming insert **8**. By thus providing the long groove **10e**, the annular groove **10d** can be placed in a position having considered gas discharge performance, that is, in a upper portion of the bore pin **10** (upward in FIGS. 1 to 3), while the hole **12a** can be placed in a position where absence of clogging can be confirmed by the operator’s observation, that is, in a lower portion of the bore pin **10** (downward in FIGS. 1 to 3). Gas discharge performance and visibility of the gas discharge path thereby can be achieved simultaneously. The long groove **10e** corresponds to the “axial groove” in the present invention as one example of a working configuration.

A through-hole **12b** having one end open to the hole **12a** and having the other end open to an end face on the installation part **10a** furthermore is formed on the holding part **10c** as illustrated in FIGS. 2 and 3. That is, the through-hole **12b** is formed in a direction following the longitudinal direction inside the holding part **10c**. The through-hole **12b** also is connected to the vacuum suction device **50** via piping not illustrated. A protruding part **10f** trapezoidal in section is formed in a protruding form on the leading end of the holding part **10c**. Although not illustrated, the protruding part **10f** is formed as an elongated protrusion following the direction of a cylinder array on a cylinder block as a manufactured product, and insertion-couples with the recessed part **4c** of the fixed mold **4** when the mold is closed. The hole **12a** corresponds to the “first hole” in the present invention, and the through-hole **12b** corresponds to the “second hole” in the present invention, as one example of a working configuration. The hole **12a** and the through-hole **12b** also correspond to the “communicating path” in the present invention as one example of a working configuration.

The operation of the mold apparatus **1** in the example thus configured, in particular the operation when an aluminum melt is poured into the cavity **30**, is next described. FIG. 5 is an explanatory diagram illustrating the manner of cast-molding using the mold apparatus **1** according to an embodiment of the present invention. In cast-molding a cylinder block, first the mold is closed. Closing of the movable mold **2** is performed in a state in which the cylinder liner **60** made of iron is held by the bore pin **10** integrally installed in the movable mold **2** via the water jacket-forming insert **8**. When the mold is closed, movement of the cylinder liner **60** in the longitudinal direction is restricted by the enlarged-diameter part **10b** of the bore pin **10** and the fixed mold **4**. In the state in which the mold is closed, a prescribed gap **CL1** is formed between the inner perimeter surface of the cylinder liner **60** and the outer perimeter surface of the holding part **10c** on the bore pin **10**, and a prescribed gap **CL2** is formed between the end face **60a** in the longitudinal-axis direction of the cylinder liner **60** and the end face **11b** of the enlarged-diameter part **10b**.

part **10b**. A volume part **V** also is formed by the inner perimeter surface of the cylinder liner **60** and the annular groove **10d** formed on the holding part **10c**. A cavity **30** configuring a shape of a cylinder block as a manufactured product is defined by closing of the mold in this manner.

At this time, an elongated blocked-off space **S** (one part of the cavity **30**) is formed by the cylinder liner **60**, the enlarged-diameter part **10b** of the bore pin **10**, the water jacket-forming insert **8**, in particular the end face **60a** in the longitudinal-axis direction of the cylinder liner **60**, the enlarged-diameter part **10b** of the bore pin **10**, and the end face of the installation part **8a** of the water jacket-forming insert **8**. The elongated blocked-off space **S** formed by the end face **60a** in the longitudinal-axis direction of the cylinder liner **60**, the enlarged-diameter part **10b** of the bore pin **10**, and the end face of the installation part **8a** of the water jacket-forming insert **8** corresponds to the “space formed by an longitudinal-direction end face of the cylinder liner, the enlarged-diameter part, and the first mold” as one example of a working configuration.

An aluminum melt is poured into the cavity **30** after the mold is closed in this manner. Here, the major part of the gas produced inside the cavity **30** during cast-molding is discharged by a gas-venting device (gas-venting valve, gas vent, or the like) not illustrated provided on the mold apparatus **1**. Meanwhile, in the cavity **30**, gas driven into the above-described elongated blocked-off space **S** flows into the prescribed gap **CL2** formed between the end face **60a** in the longitudinal-axis direction of the cylinder liner **60** and the end face **11b** of the enlarged-diameter part **10b**, and into the prescribed gap **CL1** formed between the inner perimeter surface of the cylinder liner **60** and the outer perimeter surface of the bore pin **10**. The flow speed of the gas flowing through the prescribed gaps **CL1** and **CL2** is lowered by the volume part **V**. The gas flowing into the volume part **V** is thereby effectively suctioned by the vacuum suction device **50** via the hole **12a** and the through-hole **12b**. Because the annular groove **10d** is provided in the upper portion of the holding part **10c** closer to the space **S**, the gas driven into the elongated blocked-off space **S** can be effectively discharged.

Because the gas driven into the cul-de-sac form space **S** thus can be discharged favorably, inconveniences during cast-molding of overcasting-type cylinder blocks, specifically, production of a blowhole, or the like, by gas accumulating in the space **S**, or defects of poor closeness of adhesion of the cylinder liner to the aluminum melt, more specifically, to a cylinder block configured from aluminum, can be effectively prevented. The quality of the overcasting-type cylinder block as a manufactured can be improved as a result.

Here, carbide (release agent residue), aluminum slag, or the like, adheres to the gaps **CL1** and **CL2** when the gas inside the cavity **30** passes through the gaps **CL1** and **CL2**, but because the configuration is such that the cylinder liner **60** being one constituent element of the gaps **CL1** and **CL2** is replaced each time a cylinder block is cast-molded, the carbide (release agent residue), aluminum slag, or the like, is removed by the cylinder liner **60** each time the mold is opened, and accumulation of residue in the gaps **CL1** and **CL2** can be effectively prevented. The frequency of the operation of cleaning the gaps **CL1** and **CL2** as gas discharge paths thereby can be reduced, and the casting cycle can be shortened. The operation efficiency of the casting operation thereby can be improved. Even if carbide (release agent residue), aluminum slag, or the like, adheres to the side of the bore pin **10**, being one constituent element of the gaps **CL1** and **CL2**, the carbide (release agent residue), aluminum slag, or the like, adheres to the inner perimeter surface of the cylinder liner **60** each time the mold is opened, and accumulation of residue in the gaps **CL1** and **CL2** can be effectively prevented.

aluminum slag, or the like, can be easily removed using a brush, or the like, in a state in which the bore pin **10** is installed in the movable mold **2**, and the burden on the operator associated with the cleaning operation can be alleviated.

Although the gaps **CL1** and **CL2** allow inflow of gas, the gaps are set to a size that prevents inflow of aluminum melt, and therefore there is no entry of aluminum melt into the gaps **CL1** and **CL2**. Furthermore, effective gas discharge performance can be realized by setting a median value of the tolerance for the gaps **CL1** and **CL2** such that the gaps **CL1** and **CL2** become maximal within a range of the gap through which the aluminum melt does not get inside. Because the hole **12a** is visible by the eye when the mold is opened, clogging of the hole **12a** can be confirmed.

According to the mold apparatus **1** according to the present embodiment described above, the apparatus is configured so that prescribed gaps **CL2** and **CL1** are formed between the end face **60a** in the longitudinal-axis direction of the cylinder liner **60** made of iron and the end face **11b** of the enlarged-diameter part **10b** on the bore pin **10**, and between the inner perimeter surface of the cylinder liner **60** and the outer perimeter surface of the holding part **10c** on the bore pin **10**. The configuration is such that gas driven into an elongated blocked-off space **S** (one part of the cavity **30**) formed by the end face **60a** in the longitudinal-axis direction of the cylinder liner **60**, the enlarged-diameter part **10b** of the bore pin **10**, and the end face of the installation part **8a** of the water jacket-forming insert **8** is discharged via the gaps **CL1** and **CL2**. That is, the configuration is such that the gaps **CL1** and **CL2** as gas discharge paths are formed by the cylinder liner **60**, which is replaced each time a cylinder block is cast-molded. Therefore, even if carbide (release agent residue), aluminum slag, or the like, adheres to the gaps **CL1** and **CL2** when the gas passes through the gaps **CL1** and **CL2**, the carbide (release agent residue), aluminum slag, or the like, can be removed by the cylinder liner **60** each time the mold is opened. The accumulation of carbide (release agent residue), aluminum slag, or the like, in the gaps **CL1** and **CL2** thereby can be effectively prevented. Accordingly, the frequency of the operation of cleaning of the gaps **CL1** and **CL2** as gas discharge paths can be reduced, and the time for planning or the casting preparation operation can be shortened. That is, the casting cycle can be shortened. The operation efficiency of the casting operation can be improved as a result. Even if carbide (release agent residue), aluminum slag, or the like, adheres to the side of the bore pin **10**, being one constituent element of the gaps **CL1** and **CL2**, the carbide (release agent residue), aluminum slag, or the like, can be easily removed using a brush, or the like, in a state in which the bore pin **10** is installed in the movable mold **2**, and therefore the burden on the operator associated with the cleaning operation also can be alleviated.

Also according to the mold apparatus **1** according to the present embodiment, although the gaps **CL1** and **CL2** allow inflow of gas, the gaps are set to a size that prevents the inflow of melt, and therefore there is no entry of aluminum melt into the gaps **CL1** and **CL2**. Furthermore, effective gas discharge performance can be realized by setting a median value of the tolerance for the gaps **CL1** and **CL2** such that the gaps **CL1** and **CL2** become maximal within a range of the gap through which the aluminum melt does not get inside. The operation efficiency in the casting operation thereby can be improved.

Also according to the mold apparatus **1** according to the present embodiment, because the configuration is such that the volume part **V** formed by the inner perimeter surface of the cylinder liner **60** each time the mold is opened, and accumulation of residue in the gaps **CL1** and **CL2** can be effectively prevented.

11

the cylinder liner 60 and the annular groove 10d is provided at midcourse of the route for discharging gas flowing through the gaps CL1 and CL2 to the outside, the flow speed of the gas flowing in from the gaps CL1 and CL2 can be reduced by the volume part V. The gas flowing into the volume part V thereby can be effectively suctioned by the vacuum suction device 50.

Also according to the mold apparatus 1 according to the present embodiment, because the configuration is such that the annular groove 10d is provided above the holding part 10c on the bore pin 10 and the hole 12a is provided below the holding part 10c using the long groove 10e, the gas discharge performance and visibility for confirming clogging of the hole 12a can be achieved simultaneously.

Also according to the mold apparatus 1 according to the present embodiment, because the configuration is such that the route for discharging the gas flowing through the hole 12a and the through-hole 12b, that is, through the gaps CL1 and CL2 to the outside is formed inside the bore pin 10, complication of the route for discharging the gas to the outside can be prevented. Because only opening a hole is sufficient, the route for discharging the gas to the outside can be assured simply.

In the mold apparatus 1 in the example, the configuration is such that the annular groove 10d is formed on the holding part 10c on the bore pin 10, but anything is possible provided that a route for discharging gas flowing through the gaps CL1 and CL2 to the outside can be formed. For example, the configuration may be such that a simple recessed part is formed.

In the mold apparatus 1 in the example, a case applied to cast-molding of an overcasting-type cylinder block is described, but the invention is applicable to cast-molding of cylinder blocks other than of overcasting type. In this case, the configuration should be such that the bore pin 10 does not have an enlarged-diameter part 10b, and the configuration should be such that the prescribed gap CL2 is formed between the end face 60a in the longitudinal-axis direction of the cylinder liner 60 and the installation part 8a on the water jacket-forming insert 8. In this case as well, there is provided the same effect as of the mold apparatus 1 according to the present embodiment described above, that is, the same effect that even if carbide (release agent residue), aluminum slag, or the like, adheres to the gaps CL1 and CL2 when the gas passes through the gaps CL1 and CL2, the carbide (release agent residue), aluminum slag, or the like, is removed by the cylinder liner 60 each time the mold is opened, whereby accumulation of carbide (release agent residue), aluminum slag, or the like, in the gaps CL1 and CL2 can be effectively prevented.

In the mold apparatus 1 in the example, the configuration is such that the long groove 10e is provided, but the long groove 10e also may be absent. In this case, the configuration should be such that the hole 12a is opened in the annular groove 10d.

In the mold apparatus 1 in the example, the configuration is such that the hole 12a opens in a direction perpendicular to the longitudinal direction of the holding part 10c, but the configuration may be such that the hole 12a is opened being inclined toward the longitudinal direction of the holding part 10c.

In the mold apparatus 1 in the example, the configuration is such that the through-hole 12b is formed in a direction following the longitudinal direction of the holding part 10c, but the configuration may be such that the through-hole 12b is formed being inclined toward the longitudinal direction of the holding part 10c.

12

In the mold apparatus 1 in the example, the configuration is such that the annular groove 10d is connected to the vacuum suction device 50 via two holes being the hole 12a and the through-hole 12b, but the configuration may be such that the annular groove 10d and the vacuum suction device 50 are connected by one hole.

Correspondences Between Each Constituent Element of the Embodiment and Each Constituent Element of the Present Invention

The present embodiment illustrates one example of an embodiment of the present invention. Accordingly, the present invention is not limited to the configuration of the present embodiment. Correspondences between each constituent element of the present embodiment and each constituent of the present invention are listed below.

The mold apparatus 1 corresponds to the "mold apparatus for casing a cylinder block" of the present invention as one example of a configuration.

The vacuum suction device 50 corresponds to the "mold apparatus for casting a cylinder block" of the present invention as one example of a configuration.

The movable mold 2 corresponds to the "first mold" of the present invention as one example of a configuration.

The bore pin 10 corresponds to the "bore pin" of the present invention as one example of a configuration.

The vacuum suction device 50 corresponds to the "vacuum suction device" of the present invention as one example of a configuration.

The water jacket-forming insert 8 corresponds to the "water jacket-forming insert" of the present invention as one example of a configuration.

The enlarged-diameter part 10b corresponds to the "enlarged-diameter part" of the present invention as one example of a configuration.

The holding part 10c corresponds to the "shaft part" of the present invention as one example of a configuration.

The end face 60a in the longitudinal-axis direction of the cylinder liner 60 corresponds to the "end face in a longitudinal direction of the cylinder liner" of the present invention as one example of a configuration.

The prescribed gaps CL1 and CL2 correspond to the "gap" of the present invention as one example of a configuration.

The annular groove 10d corresponds to the "recessed part" of the present invention as one example of a configuration.

The annular groove 10d corresponds to the "annular groove" of the present invention as one example of a configuration.

The long groove 10e corresponds to the "recessed part" of the present invention as one example of a configuration.

The long groove 10e corresponds to the "axial groove" of the present invention as one example of a configuration.

The hole 12a corresponds to the "first hole" of the present invention as one example of a configuration.

The hole 12a corresponds to the "communicating path" of the present invention as one example of a configuration.

The through-hole 12b corresponds to the "second hole" of the present invention as one example of a configuration.

The through-hole 12b corresponds to the "communicating path" of the present invention as one example of a configuration.

The space S corresponds to the "space formed by a longitudinal-direction end face of the cylinder liner, the enlarged-diameter part, and the first mold" of the present invention as one example of a configuration.

In view of the gist of the invention above, a mold apparatus according to the present invention can be configured with the following modes.

(Mode 1)

“A mold apparatus for casting a cylinder block, for cast-molding a cylinder block having a cast-in cylinder liner by installing the cylinder liner inside a cavity and pouring a melt into the cavity, the mold apparatus comprising:

a first mold for defining a deck surface of the cylinder block; and

a bore pin provided in the first mold so as to hold the cylinder liner inside the cavity when the mold is closed; wherein:

the bore pin holds the cylinder liner with a gap; and gas produced during the cast-molding is discharged via the gap.”

(Mode 2)

“A mold apparatus for casting a cylinder block, for cast-molding a cylinder block having a cast-in cylinder liner by installing the cylinder liner inside a cavity and pouring a melt into the cavity, the mold apparatus comprising:

a first mold for defining a deck surface of the cylinder block;

a bore pin provided in the first mold so as to hold the cylinder liner inside the cavity when the mold is closed; and a gas discharge path for discharging the gas using the gap.”

(Mode 3)

“The mold apparatus for casting a cylinder block according to mode 1 or 2, further comprising a water jacket-forming insert surrounding the cylinder liner held by the bore pin when the mold is closed; wherein:

the gas that has entered into a space inside the cavity is discharged via the gap, the space being formed by the cylinder liner held by the bore pin and by the water jacket-forming insert.”

(Mode 4)

“The bore pin according to mode 3, wherein:

the bore pin has a shaft part with which the cylinder liner is fitted, and an enlarged-diameter part provided closer to the side of the first mold than to the shaft part and formed to a larger diameter than the shaft part; and

the cylinder liner is held by the bore pin in a state in which longitudinal-direction movement of the cylinder liner is restricted by the enlarged-diameter part when the mold is closed, and the gas that has entered into a space inside the cavity is discharged via the gap, the space being formed by a longitudinal-direction end face of the cylinder liner, the enlarged-diameter part, and the water jacket-forming insert.”

(Mode 5)

“The mold apparatus for casting a cylinder block according to mode 4, wherein the gap is formed between the longitudinal-direction end face of the cylinder liner and the enlarged-diameter part, and between an inner perimeter surface of the cylinder liner and an outer perimeter surface of the shaft part.”

(Mode 6)

“The mold apparatus for casting a cylinder block according to any of modes 1 to 5, wherein the gap is configured to enable inflow of the gas but prohibit inflow of the melt.”

(Mode 7)

“The mold apparatus for casting a cylinder block according to any of modes 1 to 6, wherein the bore pin has a recessed part formed on an outer perimeter surface, and a communicating path communicating between the recessed part and the outside of the mold apparatus for casting a cylinder block.”

(Mode 8)

“The mold apparatus for casing a cylinder block according to mode 7, wherein the recessed part is configured as an annular groove continuing in a circumferential direction.”

(Mode 9)

“The mold apparatus for casing a cylinder block according to mode 7 or 8, wherein the communicating path has a first hole opened in a direction from the recessed part toward the inside of the shaft part, and a second hole opened in a direction from the first hole toward the first mold.”

(Mode 10)

“The mold apparatus for casing a cylinder block according to any of modes 2 to 6, wherein the gas discharge path has a recessed part formed on an outer perimeter surface of the bore pin, and a communicating path communicating between the recessed part and the outside of the mold apparatus for casting a cylinder block.”

(Mode 11)

“The mold apparatus for casing a cylinder block according to mode 10, wherein the recessed part is configured as an annular groove continuing in a circumferential direction.”

(Mode 12)

“The mold apparatus for casing a cylinder block according to mode 10 or 11, wherein the communicating path has a first hole opened in a direction from the recessed part toward the inside of the shaft part, and a second hole opened in a direction from the first hole toward the first mold.”

(Mode 13)

“The mold apparatus for casing a cylinder block according to mode 9 or 12, wherein:

the recessed part has an axial groove connected to the annular groove and provided extending in a longitudinal-axis direction of the bore pin from the annular groove toward a leading end side of the bore pin; and

the first hole is formed on a leading end side of the axial groove.”

(Mode 14)

“The mold apparatus for casing a cylinder block according to any of modes 7 to 13, further comprising a vacuum suction device for rendering the inside of the cavity into a vacuum state; wherein:

the communicating path communicates between the recessed part and the vacuum suction device.”

What is claimed is:

1. A mold apparatus for casting a cylinder block having a cast-in cylinder liner by installing the cylinder liner inside a cavity and pouring a melt into the cavity, the mold apparatus comprising:

a first mold configured to define a deck surface of the cylinder block;

a bore pin disposed in the first mold so as to hold the cylinder liner inside the cavity when the mold is closed; and

a gas discharge portion configured to discharge gas generated while casting, the gas discharge portion being a gap between the bore pin and the cylinder liner.

2. The mold apparatus for casting a cylinder block according to claim 1, further comprising

a water jacket-forming insert configured to surround the cylinder liner to be held by the bore pin when the mold is closed;

the gas discharge portion being arranged to enable gas that has entered into a space inside the cavity to be discharged therethrough, the space being formed by the cylinder liner held by the bore pin and by the water jacket-forming insert.

15

3. The mold apparatus for casting a cylinder block according to claim 2, wherein

the bore pin has a shaft part with which the cylinder liner is to be fitted, and an enlarged-diameter part disposed closer to the first mold than to the shaft part and having a larger diameter than the shaft part, and the enlarged-diameter part is configured to restrict the longitudinal-direction movement of the cylinder liner when the mold is closed, and the gas discharge portion is configured to enable gas that has entered into a space inside the cavity to be discharged therethrough, the space being formed by a longitudinal-direction end face of the cylinder liner, the enlarged-diameter part, and the water jacket-forming insert.

4. The mold apparatus for casting a cylinder block according to claim 1, wherein

the bore pin has a shaft part with which the cylinder liner is to be fitted, and an enlarged-diameter part disposed closer to the first mold than to the shaft part and having a larger diameter than the shaft part, and the enlarged-diameter part is configured to restrict the longitudinal-direction movement of the cylinder liner when the mold is closed, and the gas discharge portion is configured to enable gas that has entered into a space inside the cavity to be discharged therethrough, the space being formed by a longitudinal-direction end face of the cylinder liner, the enlarged-diameter part, and the water jacket-forming insert.

5. The mold apparatus for casting a cylinder block according to claim 4, wherein

the bore pin has a recessed part on an outer perimeter surface, and a communicating path arranged to com-

16

municate between the recessed part and an outside of the mold apparatus for casting a cylinder block.

6. The mold apparatus for casting a cylinder block according to claim 5, wherein

the recessed part is an annular groove extending in a circumferential direction.

7. The mold apparatus for casting a cylinder block according to claim 6, wherein

the communicating path has a first hole opened in a direction from the recessed part toward an inside of the shaft part, and a second hole opened in a direction from the first hole toward the first mold.

8. The mold apparatus for casting a cylinder block according to claim 5, wherein

the communicating path has a first hole opened in a direction from the recessed part toward an inside of the shaft part, and a second hole opened in a direction from the first hole toward the first mold.

9. The mold apparatus for casting a cylinder block according to claim 8, wherein

the recessed part has an axial groove connected to the annular groove and extends in a longitudinal axis direction of the bore pin from the annular groove toward a leading end side of the bore pin and

the first hole is on a leading end side of the axial groove.

10. The mold apparatus for casting a cylinder block according to claim 5, further comprising

a vacuum suction device configured to bring the inside of the cavity into a vacuum state,

the communicating path communicating between the recessed part and the vacuum suction device.
